UNITED STATES PATENT OFFICE.

EUGÈNE A. GERBRACHT, OF NEW YORK, N. Y.

CHILD'S CARRIAGE.

SPECIFICATION forming part of Letters Patent No. 376,591, dated January 17, 1888.

Application filed September 28, 1887. Serial No. 250,900. (No model.)

To all whom it may concern:

Be it known that I, EUGÈNE A. GERBRACHT, of the city, county, and State of New York, have invented a new and useful Improvement 5 in Children's Carriages, of which the following is a full, clear, and exact description.

My invention relates to an improvement in children's carriages, and has for its object to provide a carriage of simple and cheap construction wherein, when desired, the body of the carriage may be utilized as a cradle without detachment from its supports.

The invention consists in the construction and combination of the several parts, as will 15 be hereinafter fully set forth, and pointed out in the claim.

Reference is to be had to the accompanying drawings, forming a part of this specification, in which similar letters of reference indicate 20 corresponding parts in all the figures.

Figure 1 is a side elevation of my improved carriage. Fig. 2 is an end view of the same. Fig. 3 is a perspective detail view of one of the body-supports, and Fig. 4 is a vertical section on line $\alpha\alpha$ of Fig. 3.

In carrying the invention into effect, the axles A are provided with suitable wheels, and the said axles are held in a parallel position a proper distance apart by the lower 30 horizontal ends b of the handle B, which is curved upward and outward in the usual manner, the attachment being made by screws, bolts, or other equivalent devices.

Upon the horizontal handle-bars b, near the 35 front end and also near the curve at the rear, S-shaped springs C are attached, and upon each side set of springs longitudinal bars D are bolted.

As a support for the body D' of the carriage, segmental brackets E and E' are provided, having a short arm or extension, e, integral with each end and projecting at right angles or horizontally therefrom. The brackets are preferably constructed of a single 45 arched piece of metal, and may, as shown in Fig. 3, be an integral portion of the springs, the front brackets and springs being formed from the same piece of metal, the rear brackets and rear springs being also in one piece.

Ordinarily, in making the attachment of the

brackets to the spring-bars D, the arms e are made to abut the upper ends of the springs; and the said arms, which are of a length equal to the distance intervening the springs and the ends of the spring-bars, are attached to 55 the under side of the latter by rivets, or in any other approved manner, as illustrated in Fig. 1.

To the front and rear ends of the carriage-body, centrally the same, vertical plates E² and E³ are respectively secured, adapted to extend from a point near the upper edges of the body downward and beneath the same. At the upper end of each plate E² and E³ a threaded pin, d, is provided, which may be integral with the plates or attached thereto, the said pins being adapted to enter a suitable aperture located centrally the upper ends of the brackets, and a nut is thereupon entered upon the pins, but not to a decided bearing 70 against the face of the said brackets. By this means the carriage-body is pivotally attached to the brackets and permitted to reciprocate between the same, whereby the rocking motion, as of a cradle, is obtained.

Near the base of the rear bracket, E, a transverse rod, h, is attached, provided with a central threaded aperture, and in the plate E³, aligning the aperture in the rod h, a similar threaded aperture is provided, the two apertures aforesaid being purposed to receive a thumb-screw, h', whereby the carriage-body may, when desired, be rigidly held in a fixed position, similar to the body of ordinary carriages.

Stop-pins H may be driven or screwed in the rear outer edges at the back of the carriage-body to limit the throw thereof when employed in the capacity of a cradle.

It will be observed that the transformation 90 from a carriage to a cradle, or vice versa, is quickly and readily effected, and that by reason of the peculiar hanging of the body a fine spring effect is produced.

In the event the carriage is designed to accommodate two children, the locking device may be repeated at the front.

Having thus fully described my invention, I claim as new and desire to secure by Letters Patent—

The combination, with the running-gear, springs, and spring-bars of a child's carriage and the body of the carriage, of the brackets E and E', the plates E² and E³, attached to the ends of the body and provided with pivots, the bar b, attached to the bracket E, and a locking device carried by the bar b, all ar-

ranged for operation substantially in the manner and for the purpose set forth.

EUGÈNE A. GERBRACHT.
